UNITED STATES PATENT OFFICE.

LEE S. BURRIDGE, DECEASED, LATE OF NEW YORK, N. Y., BY FRANCIS O. BURRIDGE,
EXECUTOR, OF NEW YORK, N. Y., ASSIGNEE, BY MESNE ASSIGNMENTS, TO UNDER-
WOOD TYPEWRITER COMPANY, OF NEW YORK, N. Y., A CORPORATION OF DELA-
WARE.

TYPEWRITING-MACHINE.

1,339,806.

Specification of Letters Patent. Patented May 11, 1920.

Application filed June 6, 1918. Serial No. 238,456.

To all whom it may concern:

Be it known that LEE S. BURRIDGE, deceased, late a citizen of the United States, and late residing in the borough of Manhattan, county, city, and State of New York, invented certain new and useful Improvements in Typewriting-Machines, of which the following is a specification.

This invention relates to typewriting machines, and is herein disclosed as applied to a small typewriting machine adapted to be easily assembled so that it may be constructed cheaply, and also adapted to be built compactly and of light parts, so that it may be convenient to carry around.

In hitherto attempting to construct machines of this type, effort has been usually directed to designing a machine comprising parts which were adapted to be folded together. According to the present invention, to make the machine compact, it has been found possible to avoid folding by incorporating parts of novel shapes, weight and function, such as short type-bars having a throw considerably in excess of ninety degrees, so that the type-bars as they lie spread out on the rest-pad, usual in front-strike machines, radiate from each other to a very great extent, thus permitting the use of a comparatively small and light segment as well as of a short, light type-bar easily operated. To obtain these and other advantages, the segment may be inclined at a considerable angle to the vertical, even as much as thirty degrees, and to further increase the throw of the type-bars, the segment may be so placed relatively to the platen that the types strike the platen after having passed their vertical point. In order to effect this, and have the types strike squarely on the platen, the types swing about seven degrees past the vertical, and in striking the platen strike through a ribbon which is approximately parallel to the tangent of the platen, so that the ribbon is struck squarely by the types, and yet is not greatly twisted from the vertical plane, thus avoiding any serious tendency of the ribbon to twist.

To obtain the best utilization of this structure, it appears to be advantageous to have the typewriter include a double shift-frame, which shift-frame also includes the ribbon-spools, so that the ribbon is in no

way twisted by the platen-shift. In order 55 to have the relationship of the ribbon, the platen and the types in printing practically constant, whatever case is being printed in, the shift-frame may be so constructed as to carry the platen up in a plane parallel to 60 the ribbon and the face of the printing type. In obtaining these results, it has been found possible to utilize a light shift-frame built out of sheet-metal, which includes not only the carriage, but also the tracks on 65 which the carriage travels as well as the ribbon-spools and certain other devices.

To enable such mechanism to be easily assembled, and to avoid the concentration of the mechanism into too narrow a compass, 70 both on the shift-frame and on the body of the machine, there are provided several points at which the mechanism on the shift-frame is adapted to be attached to the mechanism on the body of the machine. 75 These connections, however, as well as the connections of the shift-frame itself to the body of the machine, may be either snap connections or screw connections, or may include stops which might have to be made 80 adjustable in any event, and, therefore, do not add to the complexity of the mechanism or the labor of assembling.

The shift-frame itself may be constructed out of separately-stamped metal parts, so 85 designed and related to each other that each part involves no serious problems in bending, and that each part is adapted to be either screwed or riveted to the other parts by openings which are adapted to be 90 formed in the process of stamping, and, at most, may only need to be provided with threads after having been stamped out.

Other features and advantages will hereinafter appear.

In the accompanying drawings,

Figure 1 is a sectional side view of a typewriting machine embodying the present improvements.

Fig. 2 is a view similar to Fig. 1, but, for 100 the most part, an end view.

Fig. 3 is a fragmentary plan view, bringing out especially the parts shown in Fig. 2.

Fig. 4 is a front view, diagrammatically 105 showing the shift-frame disconnected from the rest of the mechanism, and its relationship thereto.

Fig. 5 is a perspective view of the shift-frame, partly broken away.

Fig. 6 is a side view of the ribbon-vibrating mechanism.

5 Character keys 10, at Fig. 1, depress key-levers 11, so as to rock bell-crank 12 by means of cams 13 engaging pins 14 on the key-levers, so that the upper ends 15 of the bell-crank will draw forward links 16, to 10 which they are pivoted, thus throwing type-bars 17, to which the links are pivoted, upwardly and rearwardly, with the result that types 18 print on the platen 19. The exact structure of the type-action is disclosed 15 more in detail in co-pending application, Serial No. 874,276, filed November 27, 1914, now Patent No. 1,268,790, granted June 4, 1918, of which the present application may be regarded as a continuation in part. The 20 type-bars 17 are pivoted in a segment 20, comprising a hanger 21, said segment being inclined at an angle of about thirty degrees from the horizontal, so that when any type rises, it swings through an angle of about 25 one hundred and twenty degrees and strikes against the platen 19 a little above the center thereof. To enable the types 18 to print, there is provided a ribbon 22 mounted on spools 23, at opposite sides of the machine, and carried through a ribbon-guide 24, which comprises a flat member 25 adjacent the platen and a flat member 26 in front thereof, by which the ribbon is kept flat in front of the platen, said guide being fast 30 35 at 27^a on the shift-frame.

The ribbon 22 is normally below the printing point, so that the writing is normally visible. Whenever a key 10 is depressed, its key-lever 11 strikes a universal bar 27, 40 which is adapted to swing forwardly a rock-arm 28, which operates the ribbon mechanism. To operate this rock-arm, the universal bar 27, which is formed as a bail extending transversely of the machine and underlying all the keys, is pivoted in a pair 45 of brackets 29, at the rear of the machine, and carries a pivot 30 of a link 31, which, at its lower end, is pivotally attached to a rock-arm 32, fast on a shaft 33, to which the rock-arm 28 is likewise fast. The shaft 33 is journaled in brackets 34 secured by screws 35 to a bottom plate 36 extending across the frame. To enable the rock-arm 28 to operate the ribbon mechanism, there is pivoted 50 to it a forwardly-extending link 37, which, at its front end, is, in turn, pivoted to a nearly vertical rocking lever 38, which serves to drive the left-hand ribbon-spool 23. The lever 38 is pivoted at 39 on a 55 turned-up end 40 of a bracket 41, projecting inwardly from the flat outer face of the shift-frame. The link 37 is of such a length that the rising of the shift-frame, 60 does not materially change its relationship 65 to the rock-arm 28 and the lever 38, partly

because of the fact that in rising the shift-frame moves rearwardly slightly.

The lever 38 is pivoted not only to the link 37, but also to a horizontal floating link 43, which is adapted to vibrate the ribbon, said link being also pivoted to a link 44, carried by a pivot 45 on a bracket 46, extending forwardly and formed as the turned-over end of part of the metal of the rail 47 on which the carriage travels. The 70 exact structure by which the link 37 is able to vibrate the ribbon is shown in application, Serial No. 151,173, filed February 27, 1917, now Patent No. 1,284,055, granted November 5, 1918, of which the present application may be regarded as a continuation in part.

The connections include a turned-around lower end 48 of the lever 38, which comprises a pivot-opening adapted to be engaged by a pivot 49 on the link 43, and to be clipped in place by a spring-clip 50 for simplicity in assembling. The link 37 is likewise provided with a spring-clip 51, so that the link may be readily attached to 85 the lever 38 in assembling. The connections for vibrating the ribbon, extending from the link 43, include an extension 52 of the pivot common to the two links 43 and 44, said extension riding in a slot 53, formed 90 in a vibratory plate 54, which is connected by a light link 55 to the ribbon-vibrator proper 56, through which the ribbon is threaded. The vibrator 56 is formed as a long, narrow V-shaped member, having its 95 two legs pivoted in a shaft 57, on the shift-frame behind the left-hand ribbon-spool, and extending therefrom almost to the ribbon-guide 24, at which point it is provided with a slot 58, through which the ribbon 100 passes.

The connections to the right-hand ribbon-spool may include an identical lever 38 and an identical link 37, provided with an identical snap-pivot connection 51. The right-hand ribbon-lever 38, however, is not used for driving the ribbon-vibrator, and, therefore, lacks any extension like 48.

The shift-frame includes not only the 110 cups for the ribbon-spool and the ribbon-vibrating mechanism, but also includes the track 59 for the rear carriage rail and the track 60 for the front carriage rail, together with an upper stringer 61 and a lower stringer 62, at each end of the machine, by 115 which stringers the ribbon-spool-supports are connected to the rest of the shift-frame. To enable the shift-frame to be shifted, there are provided a single or capital-shift-key 63, and a double or figure-shift-key 64, 120 said keys being pivoted on a short shaft 65, fast in a bracket 66, which is mounted on a bottom cross-bar 67 of the main frame of the machine. When the figure-shift-key is 125 depressed, the rear end 68 of its lever strikes 130

underneath a bracket 69, fast to the bottom left-hand stringer 62 of the shift-frame, and lifts said shift-frame, causing it to rise upwardly and rearwardly. To guide the shift-frame as it goes upward, there are provided a pair of rock-arms 70, one at each side of the machine, said rock-arms fast on a transverse hollow shaft 71 journaled in the rear of the main frame, and pivoted by shouldered screws 72 to the bottom stringer 62 near the bracket 69. There are also provided a pair of guide-links 73, pivoted on standards 74, rising from the rear of the machine, said links extending forwardly and upwardly to a point somewhat below the ribbon-cups at the front of the shift-frame, at which point they are provided with shouldered screw-pivots 75.

To enable the carriage to feed past the links 73, the links are provided with U-shaped portions 76 near the carriage tracks. They are also provided with outwardly-flaring downward extensions 77, extending near to the bottom of the machine to provide anchorages for springs 78, extending to the frame, and adapted to take part of the load of the shift-frame, thus relieving the load on the shift-key when it is depressed.

In order to limit the throw of the shift-frame, the shift-frame is provided with lugs 79, which may be integral or in the form of brackets fast on the stringers 62, said brackets being provided with openings 80, adapted to surround post 81, each held by a screw 81^a and dowel pins to the side of the main frame of the machine, said posts being provided with a pair of lock-nuts 82, on which the brackets 80 normally rest, and also provided with a pair of lock-nuts 83, spaced from the first nuts, adapted to form a limiting-stop for the shift-frame when the figure-shift-key 64 is depressed.

If the single or capital-shift-key 63 is depressed, its rear end 84 strikes beneath the bracket 69, and raises the shift-frame as does the figure-shift-key 64, but, to prevent the shift-frame from being raised to the same height, there is provided a pair of normally ineffective stops 85, adapted to be swung above the brackets 79 whenever the capital-shift-key 63 is depressed. To accomplish this, the stops 85, which are in the form of set-screws provided with lock-nuts 86, are mounted in the turned-over ends of a plate 87, in the shape of a bail provided with a long, horizontal portion 88, beneath the frame, and upturned arms 89 adapted to swing on pivots 90 in the ends 60 of the side frame of the machine. To carry the stops 85 to effective position, the plate 87 is provided with a bracket 91, extending upwardly and overlying a turned-over end 92 of the rearward extension 84 of the capital-shift-key-lever, with the result that

whenever the capital-shift key is depressed, its lever swings the stops 85 to effective position over the brackets 79, against the tension of the springs 92^a, which normally hold the stops 85 in their normal ineffective position, shown at Fig. 2.

It will be observed that the shift-frame can easily be attached and detached by unscrewing the screw-pivots 72 and 75 and removing the nuts 83 (or the screws 81^a), 75 thus enabling it to be lifted from the machine. In order that there may be no other points of connection or disconnection except such as may be essential in a machine built to stand hard use and to work accurately, most of the other connections are composed of parts adapted to slide into and out of each other in the process of lifting out the shift-frame after the removal of the screw-pivots 72 and 75 and the nuts 83. 85

These other connections include the connection from the universal bar to the escapement mechanism. To enable this sliding, the escapement mechanism is mounted on the shift-frame and includes a lever or dog-rocker 93 adapted to rock horizontally to operate the escapement dogs. The details of the escapement mechanism are disclosed more fully in co-pending application, Serial No. 201,260, filed November 10, 1917, of 95 which this application may be regarded as a continuation in part.

Since the shift-frame moves slightly rearwardly as it moves upwardly in shifting, the connections, including the posts 81, 100 slant rearwardly, parallel to the movement of the platen, and the parts are adapted to permit the shift-frame to be lifted out in the same direction. To permit this, the lever 93 has an extension 94 in the shape of 105 an inverted U, slanting slightly rearwardly, in an open slot 95 of which a rod 96 is adapted to vibrate, and to move with it the lever, because the rod is provided with set-screws 97 at the rear end thereof, while 110 the front end is threaded into an abutment 98, forming part of a rocking mechanism. This rocking mechanism is on the main frame and includes a lever 99, pivoted in a bracket 100, fast on the frame of the machine, and having pivoted thereto, at its upper end, a floating link 101, of which the abutment 98 forms the rear end, while the front end rests on a pivot 102. The pivot 102 is adapted to vibrate the floating link 120 101, and thereby operate the escapement lever 93. To accomplish this, the pivot 102 rides in a slot 103, against the end of which it is held by a spring 104^a, and is mounted on the upper end of a rock-arm 125 104, fast to the shaft 33, which, it will be remembered, is rocked at every depression of the universal bar. The rock-arm 104 is, therefore, rocked at every depression of a type-key and operates the escapement lever 130

93. The lever 99 is also connected by a suitable link 105 to the space-key 106.

Another connection, adapted to be separated by the mere lifting of the shift-frame, 5 is the ribbon-reverse mechanism, which includes a rod 107, projecting downwardly from each ribbon-cup 108, and adapted to rest in open forks 109, said forks being connected together by a rod 110, which is 10 adapted to be operated by a reverse-key 111, as set forth in Patent, No. 1,249,022, dated December 4, 1917.

The mechanism is also provided with a back-space-key which is adapted to operate 15 the back-space-mechanism through connections which are readily separable for purposes of assembling and disassembling. To enable this, the back-space-mechanism is provided with a long push-link 112, mounted 20 on the shift-frame and extending to near one end thereof, where it is provided with an easily detachable connection running to the back-space-key 113. This connection may include a bell-crank 114, pivotally 25 mounted on a bracket 115 held by two screws 115^a to the frame of the machine, and having an arm 116 overlying a rearward extension 117 of the back-space-key-lever. The depression of the back-space- 30 key rocks the bell-crank and is adapted to push the link 112 by means of a pivot 118, which may be in the form of a snap-hook-connection which can be easily connected and disconnected. The exact structure 35 of the back-space-mechanism is not described herein, inasmuch as it is fully disclosed in the co-pending application, No. 205,109, filed December 3, 1917, of which the present application may be regarded as a 40 continuation in part.

From the above description, it will be seen that there is provided a shift-frame adapted to be assembled to form a unit of the machine, which can be easily attached 45 to the rest of the mechanism. Moreover, the shift-frame is so designed that the parts thereof can be assembled without material interference with each other, and that when so assembled, they fit closely, yet easily, into 50 corresponding parts on the main body of the machine frame.

It will be noted that although the ribbon-spools are on the shift-frame, and the ribbon mechanism which drives them is 55 also to a large extent, on the shift-frame, the connection from one spool to the other for reversing runs along, and is mounted on the main body of the frame, where it is not likely to be damaged, and, owing to 60 its sheltered position, can be light.

It will be noted also that the ribbon-spools have each their own driving lever 38, and that these levers are adapted to be disconnected from the links 37, which vibrate 65 them by merely springing the clip or snap-

connections 51 open. The same is true of the back-space-key-snap-connection 118. In order to hold the universal bar 27 up against the key-levers, it is provided at each side with a spring 119 anchored in an extension 70 120, springing from the bar 121, which supports the segment 20.

Variations may be resorted to within the scope of the invention, and portions of the improvements may be used without others. 75

Having thus described my invention, I claim:

1. In a typewriting machine, in combination, a main frame, a shift frame, means for so mounting said shift frame in said main 80 frame as to permit case-shift movements of one with respect to the other, a traveling carriage and its letter-spacing mechanism mounted in said shift frame, ribbon-feeding mechanism mounted in said shift frame, ribbon-vibrating mechanism mounted in said shift frame, means mounted in said main frame for operating all of said mechanisms, operating connections from said operating means to each of said mechanisms, said connections being effective irrespective of the case-shift position of said shift frame, and readily attachable and detachable connections between said shift frame and its mounting means to facilitate the assembling 95 and disassembling of the machine; the operating connections between said operating means and said letter-spacing mechanism, ribbon-feeding mechanism and ribbon-vibrating mechanism being also readily attachable and detachable, and so related, when detached, that the shift frame and all parts carried thereby may be readily assembled with and disassembled from the main frame and the parts mounted therein. 100 105

2. In a typewriting machine, in combination, a main frame, a shift frame, means for so mounting said shift frame in said main frame as to permit case-shift movements of one with respect to the other, ribbon-feeding 110 mechanism mounted in said shift frame, ribbon-reversing mechanism mounted in said shift frame, means mounted in said main frame for operating said ribbon-feeding mechanism, means mounted in said main 115 frame for operating said ribbon-reversing mechanism, operating connections from each of said operating means to its respective mechanism, said connections being effective irrespective of the case-shift position of said 120 shift frame, and readily attachable and detachable connections between said shift frame and its mounting means to facilitate the assembling and disassembling of the machine; the operating connections between 125 each of said operating means and its respective mechanism being also readily attachable and detachable, and so related, when detached, that the shift frame and ribbon-feeding and reversing mechanisms 130

mounted therein may be readily assembled with and disassembled from the main frame and the operating means mounted therein.

3. In a typewriting machine, in combination, a main frame, a shift frame, means for so mounting said shift frame in said main frame as to permit case-shift movements of one with respect to the other, a traveling carriage and its letter-spacing mechanism mounted in said shift frame, means mounted in said main frame for operating said letter-spacing mechanism, an operating connection between said operating means and said letter-spacing mechanism, said connection being effective irrespective of the case-shift position of the shift frame, and readily attachable and detachable connections between said shift frame and its mounting means to facilitate the assembling and disassembling of the machine; the operating connection between said letter-spacing mechanism and its operating means being also readily attachable and detachable, and so related, when detached, that the shift frame with its carriage and letter-spacing mechanism may be readily assembled with and disassembled from the main frame and the operating means mounted therein.

4. In a typewriting machine, in combination, a main frame, a shift frame, means for so mounting said shift frame in said main frame as to permit case-shift movements of one with respect to the other, a traveling carriage and its letter-spacing mechanism mounted in said shift frame, a back-spacing mechanism for said letter-spacing mechanism, means mounted in said main frame for operating said letter-spacing mechanism, means mounted in said main frame for operating said back-spacing mechanism, operating connections from each of said operating means to its respective mechanism, said connections being effective irrespective of the case-shift position of said shift frame, and readily attachable and detachable connections between said shift frame and its mounting means to facilitate the assembling and disassembling of the machine; the operating connections between each of said operating means and its respective mechanism being also readily attachable and detachable, and so related, when detached, that the shift frame and mechanisms mounted therein may be readily assembled with and disassembled from the main frame and the operating means mounted therein.

5. In a typewriting machine, the combination with a main frame and a universal bar thereon, of a shift-frame including a traveling carriage and tracks on which the carriage runs, two ribbon-supports also forming part of the shift-frame, ribbon-drive mechanism adapted to be operated by said universal bar, a ribbon-reverse mechanism including a post movable on each rib-

bon-support to control individually the drive mechanism for each ribbon-support, a link shiftable on the main frame adapted to engage said supports to reverse the ribbon, and a fork for each post connected to said link, from which the posts are adapted to be separated by lifting the shift-frame. 70

6. In a typewriting machine, the combination with a main frame and a universal bar thereon, of a shift-frame including a traveling carriage and tracks on which the carriage runs, two ribbon-supports also forming part of the shift-frame, ribbon-drive mechanism adapted to be operated by said universal bar, a ribbon-reverse mechanism including a post movable on each ribbon-support, to control individually the drive mechanism for each ribbon-support, a link shiftable on the main frame, a fork for each post connected to said link, from which the posts are adapted to be separated by lifting the shift-frame, links pivoted on the main frame for guiding the shift-frame, and removable screw-pivots by which said links are pivoted to the shift-frame. 80 90

7. In a typewriting machine, the combination with a main frame and a universal bar thereon, of a shift-frame including a traveling carriage and tracks on which the carriage runs, an escapement mechanism on said shift-frame, a lever forming part of said escapement mechanism comprising a U-shaped opening, a rod comprising abutments and vibrated by said universal bar, said rod adapted to rest in said U-shaped opening to 95 vibrate the lever and to be separated therefrom by lifting the shift-frame, two ribbon-supports also forming part of the shift-frame, ribbon-drive mechanism adapted to be operated by said universal bar, a ribbon-reverse mechanism including a post movable on each ribbon-support, to control individually the drive mechanism for each ribbon-support, a link shiftable on the main frame, and a fork for each post connected to said link, from which the posts are adapted to be separated by lifting the shift-frame. 100 110

8. In a typewriting machine, the combination with a main frame and a universal bar thereon, of a shift-frame including a traveling carriage and tracks on which the carriage runs, an escapement mechanism on said shift-frame, a lever forming part of said escapement mechanism comprising a U-shaped opening, a rod comprising abutments and vibrated by said universal bar, said rod adapted to rest in said U-shaped opening to vibrate the lever and to be separated therefrom by lifting the shift-frame, two ribbon-supports also forming part of the shift-frame, ribbon-drive mechanism adapted to be operated by said universal bar, a ribbon-reverse mechanism including a post movable on each ribbon-support, to control individually the drive mechanism 115 120 125 130

for each ribbon-support, a link shiftable on the main frame, a fork for each post connected to said link, from which the posts are adapted to be separated by lifting the 5 shift-frame, a back-space-link connected to said escapement mechanism and extending along the shift-frame, a back-space-key-lever at the front of the machine, and an easily detachable connection between said 10 back-space-key-lever and said back-space-link.

9. In a typewriting machine, the combination with a main frame and a universal bar thereon, of a shift-frame including a 15 traveling carriage and tracks on which the carriage runs, an escapement mechanism on said shift-frame, a lever forming part of said escapement mechanism comprising a U-shaped opening, a rod comprising abutments and vibrated by said universal bar, 20 said rod adapted to rest in said U-shaped opening to vibrate the lever and to be separated therefrom by lifting the shift-frame, two ribbon-supports also forming part of 25 the shift-frame, ribbon-drive mechanism adapted to be operated by said universal bar, a ribbon-reverse mechanism including a post movable on each ribbon-support, to control individually the drive mechanism for 30 each ribbon-support, a link shiftable on the main frame, a fork for each post connected to said link, from which the posts are adapted to be separated by lifting the shift-frame, links between said main frame and 35 said shift-frame, and easily removable pivots by which the links are pivoted to the shift-frame.

10. In a typewriting machine, the combination with a main frame and a universal bar thereon, of a shift-frame including a 40 traveling carriage and tracks on which the carriage runs, an escapement mechanism on said shift-frame, a lever forming part of said escapement mechanism comprising a U-shaped opening, a rod comprising abutments and vibrated by said universal bar, 45 said rod adapted to rest in said U-shaped opening to vibrate the lever and to be separated therefrom by lifting the shift-frame, two ribbon-supports also forming part of the shift-frame, ribbon-drive mechanism adapted to be operated by said universal bar, a ribbon-reverse mechanism including a post movable on each ribbon-support, to control 50 individually the drive mechanism for each ribbon-support, a link shiftable on the main frame, a fork for each post connected to said link, from which the posts are adapted to be separated by lifting the shift-frame, a back-space-link connected to said 55 escapement mechanism and extending along the shift-frame, a back-space-key at the front of the machine including a lever ex-

tending to the rear, an easily detachable connection between said back-space-key-lever 65 and said back-space-link, links between said main frame and said shift-frame, and easily removable pivots by which the links are pivoted to the shift-frame.

11. In a typewriting machine, in combination, a main frame, a shift frame, means for so mounting said shift frame in said main frame as to permit case-shift movements of one with respect to the other, ribbon-feeding mechanism mounted in said shift frame, 70 means mounted in said main frame for operating said ribbon-feeding mechanism, an operating connection between said operating means and said ribbon-feeding mechanism, said connection being effective irrespective of the case-shift position of said shift frame, and readily attachable and detachable connections between said shift frame and its mounting means to facilitate the assembling and disassembling of the machine; the operating connection between 75 said ribbon-feeding mechanism and its operating means being also readily attachable and detachable, and so related, when detached, that the shift frame and ribbon-feeding mechanism mounted therein may be 80 readily assembled with and disassembled from the main frame and the operating means therein.

12. In a typewriting machine, in combination, a main frame, a shift frame, means for so mounting said shift frame in said main frame as to permit case-shift movements of one with respect to the other, ribbon-feeding mechanism mounted in said shift frame, ribbon-vibrating mechanism mounted in said shift frame, means mounted in said main frame for operating both of said mechanisms, operating connections from said operating means to each of said mechanisms, 95 said connections being effective irrespective of the case-shift position of the shift frame, and readily attachable and detachable connections between said shift frame and its mounting means to facilitate the assembling 100 and disassembling of the machine; the operating connections between said ribbon-feeding and ribbon-vibrating mechanisms and their operating means being also readily attachable and detachable, and so related, 105 when detached, that the shift frame and mechanisms mounted therein may be readily assembled with and disassembled from the main frame and its operating means.

FRANCIS O. BURRIDGE,
Executor of the last will and testament of
Lee S. Burridge, deceased.
